COMPACT BARBECUE GRILL

Merlin W. Ehrlichmann, Minnetonka, Minn., assignor to West Creek Co., Inc., Minnetonka, Minn.

Filed Jan. 7, 1971, Ser. No. 104,845

Term of patent 14 years

Int. Cl. D7—02

U.S. Cl. D81—10

Fig. 5

Fig. 6

FIG. 1 is a front elevational view of a compact barbecue grill embodying my new design;

FIG. 2 is a side elevational view thereof;

FIG. 3 is a rear elevational view thereof;

FIG. 4 is a top plan view thereof taken as on line 4-4 in FIG. 2;

FIG. 5 is a perspective view thereof; and

FIG. 6 is a bottom plan view thereof.

I claim:

The ornamental design for a compact barbecue grill, substantially as shown.
